UNITED STATES PATENT OFFICE.

LOUIS K. DOELLING, OF NEW ROCHELLE, NEW YORK, ASSIGNOR TO DE LA VERGNE MACHINE COMPANY, A CORPORATION OF NEW YORK.

PUMP.

No. 877,492.

Specification of Letters Patent.

Patented Jan. 28, 1908.

Application filed April 17, 1907. Serial No. 368,614.

To all whom it may concern:

Be it known that I, LOUIS K. DOELLING, a subject of the Emperor of Germany, residing at New Rochelle, in the county of Westchester and State of New York, have invented a certain new and useful Improvement in Pumps, of which the following is a specification, reference being had therein to the accompanying drawings, forming a part 10 thereof.

My invention relates generally to pumps and more particularly to what are known as "variable delivery" pumps, and has for its general objects simplicity of construction and 15 efficiency of operation.

A particular object is the more efficient and simplified regulation of certain types of internal combustion engines.

My invention includes the provision of 20 proved means for causing delivery to take place only during a predetermined portion of a complete cycle of operations of the pump. This not only permits a variation at will of the amount or quantity of delivery, 25 but also permits of the delivery being so timed as to take place only within a desired fractional portion of a complete cycle of operations of the pump. Such a result would be of utility for various purposes, one of 30 which is the regulation of gas-engines both by properly timing the fuel delivery and by varying the quantity of fuel supplied to the engine.

My invention also includes the provision of 35 means for varying the effective travel of a pump-piston while the actual travel of the piston remains the same. It is in many instances desirable to vary at will the delivery of a pump in each cycle without altering the 40 extent of travel of the pump piston, such extent of travel being the length of stroke in a reciprocating pump and the circumferential path of the rotary piston in a rotary pump. An example of such advantage in 45 the case of reciprocating pumps would be in a gas-engine having the piston-rod of the fuel-gas pump extended and forming also a piston-rod for an air-supply pump, it being desired to vary the delivery of the gas-pump 50 without interfering with the operation of the air-pump. For a reciprocating pump the effective piston travel is substantially equivalent to the effective cylinder length. In a reciprocating pump, according to my invention, slots or regulating ports are pro-

vided in the pump-cylinder, arranged successively longitudinally of such cylinder in the path of the delivery end of the piston and so as to be successively covered or closed by the advancing piston, such regulating-ports 60 being controlled by a regulating-valve by which they may be opened and closed in the proper succession to produce the desired result of varying the effective cylinder length.

My invention also includes the arrangement of the slots or regulating-ports in a plurality of rows with the ports of one row opposite the closed spaces or bridges of another row so as to effect a continuous regulation or a regulation but slightly intermittent 70 or variable.

My invention also includes the provision of means for rendering the maximum effective piston travel of a pump permanently less than the total actual piston travel, thus 75 permanently reducing what would otherwise be the full delivery of the pump or timing the delivery to a portion of the cycle of operations of the pump corresponding to or having a certain relation with some other 80 part, or effecting both of these results. An example of the latter purpose or function would be in the case of a gas engine such as above mentioned in which the fuel-gas pump and the air-supply pump have a piston-rod 85 in common, it being desirable to time the delivery of gas and air relatively to each other so that fuel-gas will not be supplied to the engine until some time after the supply of air thereto has commenced.

My invention further includes the provision of governor-controlled means for varying the effective travel of a pump piston while the actual travel of the piston remains the same, thereby automatically varying the 95 delivery of the pump. Means embodying this feature of my invention comprise a governor operatively connected to the regulating-valve.

My invention also includes various improvements in the construction and combination of parts, and has other objects and advantageous features, as will appear from the following description.

I will now particularly describe the embodiments of my invention illustrated in the accompanying drawings and will thereafter point out my invention in claims.

Figure 1 is a plan view of a Koerting gas-engine equipped with a gas-pump embody-

105

110

ing my present invention, with parts of the engine broken away. Fig. 1^a is an inverted sectional plan of the upper half of the gas-pump cylinder showing the unloading port and the regulating ports. Fig. 2 is a side elevation of the same, with the gas-pump in section, the plane of section as to the ports thereof being indicated by the line 2—2, Fig. 1^a. Fig. 3. is a central vertical transverse section of the gas-pump. Fig. 4 is an enlarged elevation of the upper portion of the gas-pump, and adjacent parts, in section on the line 4—4, Fig. 5. Fig. 5 is an enlarged plan view of the same in section on the line 5—5, Fig. 4. Fig. 6 is a sectional elevation of a modification showing a single-acting reciprocating pump, with all ports controlled by the regulating valve. Fig. 7 is a similar view of another modification showing a single acting pump in which the maximum delivery represents only a portion of the entire stroke of the piston. Fig. 8 is a sectional elevation of a modified double-acting pump in which regulation may be had from full delivery to any fractional portion thereof. The plane of section of the parts is in rear of the center, as indicated by the line 8—8, Fig. 9. Fig. 9 is an inverted sectional plan of the upper half of the cylinder of Fig. 8, showing the regulating ports therein. Fig. 10 is a horizontal sectional detail of one of the cages for the regulating-valves. Fig. 11 is a vertical section of the ports and valves on a plane forward of the center as indicated by the line 11—11, Fig. 9.

In the embodiment of my invention illustrated in Figs. 1 to 5 inclusive I have shown my improved pump, as employed, under governor control, to deliver a variable quantity of fuel gas to a gas-engine, according to the demands or needs of the engine. The gas-engine, illustrated to the extent necessary, is a double-acting two-cycle gas engine of the well known Koerting type.

Within the gas-pump cylinder 11 is a piston 12 having a piston rod 13 to which is pivotally connected, at a slide or cross-head 14, a connecting-rod 15 which is also pivoted on a crank pin 16 carried by a crank-disk 17 on the main shaft 18 of the engine, this main shaft having bearings as shown on the frame or base 19. The crank-disk 17 is, as usual, properly timed upon the shaft 18 in relation to the engine-crank 20 so that the gas-pump will deliver its charges to the working cylinder or engine-cylinder 21 at proper times in the cycles of operation of the engine. As the gas-pump is double-acting, to correspond with the engine, its cylinder 11 has inlet ports or suction-ports 22 at each end thereof. These inlet-ports 22 communicate with passages 23 formed by valve-plates 24 having ports therethrough controlled by usual inwardly-opening inlet-valves or suction-valves 25, the valve plates 24 being

supported as shown in a valve-chest or inlet-chamber 26 into which opens a supply-conduit or induction-pipe 27 which may lead from any suitable source of gas supply. The gas-pump discharges or delivers the gas through delivery ports in its cylinder-heads 28, such ports being controlled by usual outwardly opening outlet-valves or delivery-valves 29. As these outlet-valves 29 and the inlet-valves 25 are of usual construction they are shown only diagrammatically in Fig. 2, but two of the former may be seen on a larger scale in Fig. 4, and all are of similar construction. Delivery takes place from the crank end of the gas-pump cylinder into an annular space 30, and delivery takes place from the head end of the gas-pump cylinder into a similar annular space 31. The annular gas-receiving space 30 communicates with a passage 32 to which are serially connected the gas-carrying conduits or pipes 33 and 34 leading to the crank end of the main cylinder or working cylinder 21, and the annular gas-receiving space 31 communicates with a passage 35 to which are connected in series the gas-carrying conduits or pipes 36 and 37 leading to the head end of the working cylinder 21.

The engine has a usual air-supplying pump having an air-cylinder 38 from which lead air-carrying conduits 39 and 40. The piston-rod 13 of the gas-pump is extended to form a tail-rod 41 forming a piston-rod for the air-pump cylinder 38.

It is desirable and, as is well known, is the practice in engines of this type to time the delivery of air and gas to the working cylinder so that air only is at first supplied, to separate the products of combustion from the succeeding combustible mixture, and later the combustible mixture of gas and air is supplied. The means for thus delaying the delivery of the fuel-gas comprise in the present invention means for causing delivery of gas from the gas-pump to take place only during the later portion of travel of the gas-pump piston, and this result is attained by a shortening of the maximum effective length of the gas-pump cylinder as compared to the length of the stroke of its piston, such maximum effective cylinder length being less than the length of piston stroke, and thus the effective piston travel is rendered less than the total actual piston travel. The means for shortening the maximum effective length of the gas-pump cylinder include a medial slot or unloading-port 42 therein. This slot 42 opens into a chamber or valve-chest 43 which in turn communicates by a passage-way 44 with the inlet-chamber 26 (see Fig. 3). This medial communication of the cylinder 11 with the inlet-chamber 26, as is apparent from the drawings, is permanent, as the slot is always open. It is evident that under no circumstances can

delivery of gas under pressure through the outlet-valves 29 take place until after the slot 42 has been covered by the piston 12. As shown in the drawings such slot would 5 not be thus covered until the piston 12 has traveled through about forty to fifty per cent. of its complete stroke, which would result in a maximum delivery of substantially between fifty and sixty per cent. of what 10 without such communication would be the total delivery capacity of the pump, and it should be noted that delivery takes place only during the later portion of the stroke of the gas-pump piston 12. The maximum 15 effective cylinder length is determined by the width of the medial slot. As the medial slot extends equally towards opposite ends of the cylinder the maximum delivery displacement of the piston 12 will be the same 20 in either direction of its movement.

For regulating the engine to agree with variations in its load, governor-controlled means are provided for varying the effective travel of the fuel-pump piston 12 while the 25 actual travel of such piston remains the same. This effect or result is brought about by varying the effective length of the cylinder 11 of the gas-pump. The means for thus varying the effective cylinder length include 30 regulating slots or regulating-ports extending transversely of the cylinder 11 and in rows parallel with its axis. Slots 45 are arranged for one end or half of the cylinder 11 of the double-acting pump and similar slots 35 46 are similarly but oppositely arranged for the other half or end of such cylinder. The slots 45 are disposed successively from a point adjacent to the medial slot 42 towards the head end of the cylinder, and the slots 40 46 are likewise successively disposed from a point adjacent to the medial slot 42 towards the crank end of the cylinder. The slots 45 and 46 are arranged in two rows, with the 45 slots of one row opposite the closed spaces or bridges between the slots of the other row, as particularly shown in Fig. 1^a, so that the regulation may be continuous and not interrupted by the bridges between the slots. The slots 45 communicate respectively with 50 ports or passages 47 which open circumferentially into a cylindrical housing or valve-cage 48 at respective successive circumferential points thereof. The slots 46 communicate respectively with ports or passages 49 which open circumferentially into a cylindrical housing or valve-cage 50 at respective successive circumferential points thereof. The ports 47 and 49 at their points of opening into the respective housings 48 and 50 55 are elongated axially of the housings into comparatively narrow slots, as may be seen in Fig. 5. The housings 48 and 50 also have wider slots or openings 51 and 52 communicating with the chamber 43. Thus the head 60 end of the cylinder 11, outwardly from the

medial slot 42, has communication, through slots 45, ports 47, valve-cage 48, chamber 43 and passage 44, with the inlet-chamber 26; and likewise the crank end of the cylinder, for a space corresponding to the slots 46, has 70 a like communication with the suction-chamber 26. The ports or passages 47 are controlled by a partially rotatable substantially semi-cylindrical regulating-valve 53, and the ports or passages 49 are controlled by a similar 75 but oppositely arranged regulating-valve 54. The regulating-valve 53 is supported and pivoted on a pivot-pin 55 at one end and is fixed at its other end on a valve-rocking shaft 56 supported in a bearing 57; and the 80 regulating-valve 54 is similarly mounted on a pivot-pin 58 and valve-rocking shaft 59 having a bearing 60.

The valves 53 and 54 are rotatable to cover a greater or lesser number of the ports 85 47 and 49 respectively. When these ports are all covered the effective length of the cylinder 11 will be measured each way from the medial slot 42, that is, the result will be the same as if the slots 45 and 46 did not 90 exist. As the ports 47 and 49 are progressively uncovered, thus opening communication between the chamber 43 and cylinder 11 through successive slots 45 and 46 successively from the middle towards the ends 95 of the cylinder, the effective length of the cylinder will be correspondingly shortened, until, when all of such ports have been uncovered, the cylinder will then be reduced to a minimum effective length equal to the 100 distance from the outermost slot 45 or 46 to the limit of travel of the piston 12 at the corresponding end of the cylinder, and, as the clearance would be small as shown in the drawings, such minimum effective length 105 would be substantially from the outermost slots 45 and 46 respectively to the corresponding cylinder heads 28.

As the slots 45, ports 47, valve-cage 48 and regulating-valve 53 are laterally oppositely arranged or disposed as compared with the slots 46, ports 49, valve-cage 50 and regulating-valve 54, to correspond to the opposite ends of the cylinder 11, it is evident that the valves 53 and 54 must be 110 rotated in opposite directions to effect a corresponding regulation at opposite ends of the cylinder. To effect this regulation simultaneously and concurrently, the valves 53 and 54 are connected or coupled together 115 to rotate together in opposite directions by a cross-connecting link 61 pivoted to substantially oppositely extending cranks 62 and 63 fixed respectively on the valve-rocking shafts 56 and 59. The regulating-valves 53 and 54 120 may be thus rocked by an operating-rod 64 shown as also pivoted to the crank-arm 63. To effect the desired automatic regulation it is obvious that it is only necessary to connect to the operating-rod 64 any preferred form 130

of automatic or speed-influenced governor, and I have accordingly shown a centrifugal governor as operatively connected to the operating-rod 64.

5 The governor connections to the regulating-valve operating-rod 64 include a bell-crank lever 65 pivotally supported on a stationary arm or bracket extending from and forming a part of a governor frame or base 10 67, one arm of the bell-crank lever being pivoted to the operating-rod 64 and the other arm thereof being pivoted to a substantially vertical link 68 connected to a governor lever 69. The governor is shown as driven 15 from the main engine-shaft 18 in usual manner. The governor connections are such that an increase of engine speed above normal raises the governor lever 69 and thus, as will be apparent from the above description, increases the extent of the opening for 20 the return of the fuel-gas to the supply-conduit and correspondingly reduces the supply of fuel-gas to the engine. On the other hand, should the engine speed drop below normal 25 the governor will depress its lever 69 and thus actuate the regulating-valves 53 and 54 to diminish the opening for the return of fuel-gas to the supply-conduit so that the gas-pump will then deliver a greater quantity 30 of fuel-gas to the engine. With the two rows of offset regulating-slots, as shown and above described, each movement of the regulating-valves will cause a change of the amount of opening between the cylinder and 35 the supply-conduit, and a very even regulation will be attained.

In the modified construction shown in Fig. 6 the invention is shown as applied to a single-acting pump which may be employed for 40 any desired purpose, as, for example, a single acting blower. A cylinder 70 has a piston 71 which may be reciprocated by a piston-rod 72. The cylinder is provided with an inlet-valve or supply-valve 73 controlling communication with a supply-conduit or intake-pipe 74 and is provided with an outlet-valve or delivery-valve 75 controlling communication with a discharge-conduit or delivery-pipe 76, the direction of flow being shown by 45 arrows. The cylinder is provided longitudinally thereof with one row of four regulating-slots 77 communicating respectively with ports or passages 78 which open successively circumferentially into a cylindrical 50 valve-cage or housing 79. The valve-cage 79 also has communication, through a return passage or overflow-duct 81, with the supply-conduit or intake-pipe 74. Communication of the cylinder 70 with the supply-conduit 74, through slots 77, ports 78, valve-cage 79, and return-pipe 81, is controlled by 55 a partially rotatable frictionally cylindrical regulating-valve 82 in control of the ports 78 in the same manner as in the operation of 60 the construction first-above described. The

regulating-valve 82 is controllable by an operating-lever 83 secured on a shaft 84 on which is fixed the valve 82. If all of the ports 78 are covered by the valve 82 then the cylinder 70 will make delivery up to the full capacity of the stroke of the piston 71. If the valve 82 should be rocked so that all of the ports 78 are uncovered then the effective length of the cylinder will be reduced to the minimum and can be no more than that portion of the cylinder extending from its bottom or head to the first adjacent slot 77. Intermediate effective cylinder lengths are secured by intermediate positions of the regulating-valve 82. In the drawings the first slot 77 at the outer or open end of the cylinder is shown as having communication with the supply-conduit 74; therefore, in this instance, delivery into the discharge-conduit 76 would not begin until after the piston 71 has passed such slot, the piston being shown in the drawings as at the outer limit of its stroke.

When in single-acting pumps it is desired that the maximum delivery shall represent only a portion of the complete stroke of the piston the modified construction shown in Fig. 7 may be employed. In the construction there shown a pump-cylinder 85 has a piston 86 reciprocatable by a piston-rod 87, and is provided with an inlet-valve 88 and outlet-valve 89 controlling communication respectively with a supply-conduit 90 and discharge-conduit 91, direction of flow being indicated by arrows. The cylinder 85 is provided longitudinally thereof with one row of three regulating-slots 92 communicating respectively with passages 93 opening successively circumferentially into a valve-cage or housing 94. The valve-cage 94 also communicates with a return-passage or overflow-duct 96 which communicates with the supply-conduit 90. The ports 93 are controllable by a partially rotatable fractionally cylindrical regulating-valve 97. To effect regulation the regulating-valve may be circumferentially shifted by an operating lever 98 fixed on a shaft 99 which carries the valve. The construction and operation as so far described are substantially the same as were described in reference to Fig. 6. In the construction shown in Fig. 7, to effect a maximum delivery which will correspond to only a portion of the complete stroke, the cylinder 85, outwardly from the slots 92, has a permanent communication with the supply-conduit 90, this communication being effected through a slot 100 opening into a passageway 101 which connects with the return-passage 96. In the drawings the piston 86 is shown at its outward limit of movement, and it is evident that under no circumstances can delivery from the cylinder 85 take place into the discharge-conduit 91 until after the piston has covered the slot 100, after which the

point at which delivery will begin will be determined by the position of the regulating-valve 97.

A further modified construction is illustrated in Figs. 8, 9, 10 and 11, which shows the invention as applied to a double-acting pump in which regulation may be had from full delivery to any desired percentage of full delivery. A cylinder 102 has therein a piston 103. The cylinder is closed at both ends as shown and each head thereof is provided with an inlet-valve 104 and with an outlet-valve 105. The piston is carried by a piston-rod 106 which passes out of the cylinder at both ends thereof through ordinary packing-glands 107. The inlet-valves 104 control communication of the cylinder with supply-conduits 108, and the outlet-valves 105 control communication of the cylinder with discharge-conduits 109, the direction of flow being indicated by arrows. In this construction the thickness of the piston 103 is about equal to the length of its stroke. Two rows of regulating-slots 110 are provided longitudinally throughout the length of the cylinder 102, the slots in the two rows being offset or alternated with each other and being of such a width as to be contiguous longitudinally of the cylinder, as may be seen in Fig. 9, the construction in this respect resembling that shown in the principal views of the drawings. At each side of a medial point longitudinally of the cylinder the regulating-slots 100 communicate with regulating-ports or passages 111 opening circumferentially into a cylindrical valve-cage 112. As shown in the drawings there are eight regulating-slots in one of the rows and seven regulating-slots in the other row. This arrangement of an odd number of slots in one row and an even number in the other is preferable in the present construction, as it results in one of the slots being a medial slot relatively to the cylinder. This medial regulating-slot, as may be seen in Fig. 11, has communication through twin ports 111 with both of the valve-cages 112, and thus serves for regulating purposes for both longitudinal halves of the cylinder in both directions of movement of the piston. The ports for the two rows of slots are arranged in circumferential rows side by side axially of the valve-cages 112 as may be seen in Fig. 10, and the valve-cages 112 also have a permanently open communication with the supply-conduits 108. Fractionally cylindrical partially rotatable regulating-valves 114 are located respectively in the valve-cages 112 in control of the ports 111. To effect a like regulation in the longitudinal halves of the cylinder the regulating-valves 114 are coupled together to rotate in opposite directions by a cross-connecting link 115 pivoted to substantially oppositely extending cranks 116 and 117 fixed on respective shafts 118

carrying the respective regulating-valves 114. The regulating-valves may be actuated by an operating-rod 119 shown as pivoted to the crank 117.

It is obvious that various modifications 70 may be made in the constructions shown and above particularly described within the principle and scope of my invention.

I claim:

1. A pump comprising a cylinder, a piston 75 therein, the cylinder having a regulating-port located in the path of the delivery end of the piston so as to be closed by the advancing piston at an intermediate point of piston travel, and a regulating valve in control of the regulating-port, whereby the effective portion of the travel of the piston may be varied to vary the delivery of the pump.

2. A pump comprising a cylinder, a piston 85 therein, the cylinder having a plurality of regulating-ports located at successively different points in the path of the delivery end of the piston so as to be successively closed by the advancing piston, and regulating 90 means in control of the regulating-ports and arranged to successively open the regulating-ports in the order of the direction of the delivery movement of the piston and to successively close the regulating-ports in the 95 reverse order, whereby the delivery of the pump may be varied by successive degrees between minimum and maximum.

3. A pump comprising a cylinder, a piston 100 therein, the cylinder having a regulating-port located in the path of the delivery end of the piston so as to be closed by the advancing piston at any intermediate point of piston travel, a regulating-valve in control of the regulating-port, and an automatic governor 105 in control of the regulating-valve.

4. A pump comprising a cylinder, a piston therein, the cylinder having a plurality of regulating-ports located at successively different points in the path of the piston so as 110 to be successively closed by the advancing piston, regulating means in control of the regulating-ports and actuatable to successively open the regulating-ports in the order of the delivery movement of the piston and 115 to close the regulation-ports in the reverse order, and an automatic governor in control of the regulating means.

5. A pump comprising a cylinder, a piston 120 therein, the cylinder having a plurality of regulating-ports located at successively different points in the path of the piston and arranged to be successively closed by the advancing piston, and regulating means in control of the regulating-ports and actuatable 125 to open the regulating-ports successively in the order of the direction of the delivery movement of the piston and to close the regulating ports successively in the reverse order, whereby the delivery of the pump may 130

be varied by successive degrees between minimum and maximum, the cylinder also having an unloading-port arranged so as to be closed by the piston in advance of the regulating-port, whereby the maximum delivery of the pump represents but a portion of the total travel of the piston.

6. A pump comprising a cylinder, a piston therein, the cylinder having a plurality of regulating-ports at successively different points in the path of the delivery end of the piston, the regulating-ports being arranged in a plurality of rows with ports of one row opposite the closed spaces of another row, and regulating means in control of the regulating-ports and actuatable to open the regulating-ports successively in the order of the direction of the delivery movement of the piston and to close the regulating-ports successively in the reverse order.

7. A pump comprising a cylinder, a piston therein, the cylinder having a plurality of regulating-ports at successively different points in the path of the delivery end of the piston, the regulating-ports being arranged in a plurality of rows with ports of one row opposite the closed spaces of another row, regulating means in control of the regulating-ports and actuatable to open the regulating-ports successively in the order of the direction of the delivery movement of the piston and to close the regulating-ports successively in the reverse order, and an automatic governor in control of the regulating means.

8. A pump comprising a cylinder, a piston therein, the cylinder having a plurality of regulating-ports at successively different points in the path of the delivery end of the piston, the regulating-ports being arranged in a plurality of rows with ports of one row opposite the closed spaces of another row, the cylinder also having an unloading-port arranged so as to be closed by the piston in advance of the regulating ports, and regulating means in control of the regulating-ports and actuatable to open the regulating-ports successively in the order of the direction of the delivery movement of the piston and to close the regulating-ports successively in the reverse order.

9. A double-acting pump comprising a cylinder, a reciprocatable piston therein, the cylinder in each longitudinal half thereof having a plurality of regulating-ports arranged at successively different points in the path of the piston so as to be successively closed by the advancing piston, and regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order,

whereby regulation of delivery may be effected in both directions of piston movement.

10. A double-acting pump comprising a cylinder, a reciprocatable piston therein, the cylinder in each longitudinal half thereof having a plurality of regulating-ports arranged at successively different points in the path of the piston, the regulating-ports for each cylinder half being arranged in a plurality of rows with the ports of one row opposite the closed spaces of another row, so as to be successively closed by the advancing piston, and regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order.

11. A double-acting pump comprising a cylinder, a reciprocatable piston therein, the cylinder in each longitudinal half thereof having a plurality of regulating-ports arranged at successively different points in the path of the piston so as to be successively closed by the advancing piston, the cylinder also having an unloading-port located between the regulating-ports belonging to the opposite longitudinal halves of the cylinder, and regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order.

12. A double-acting pump comprising a cylinder, a reciprocatable piston therein, the cylinder in each longitudinal half thereof having a plurality of regulating-ports arranged at successively different points in the path of the piston, the regulating-ports for each cylinder half being arranged in a plurality of rows with the ports of one row opposite the closed spaces of another row, so as to be successively closed by the advancing piston, the cylinder also having an unloading-port located between the regulating-ports belonging to the opposite longitudinal halves of the cylinder, and regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order.

13. A double-acting pump comprising a cylinder, a reciprocatable piston thereof, the cylinder in each longitudinal half thereof having a plurality of regulating-ports arranged at successively different points in the

path of the piston so as to be successively closed by the advancing piston, regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order, and an automatic governor in control of the regulating means.

14. A double-acting pump comprising a cylinder, a reciprocatable piston therein, the cylinder in each longitudinal half thereof having a plurality of regulating-ports arranged at successively different points in the path of the piston, the regulating-ports for each cylinder half being arranged in a plurality of rows with the ports of one row opposite the closed spaces of another row, so as to be successively closed by the advancing piston, regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order, and an automatic governor in control of the regulating means.

15. A double-acting pump comprising a cylinder, a reciprocatable piston therein, the cylinder in each longitudinal half thereof having a plurality of regulating-ports arranged at successively different points in the path of the piston, the regulating-ports for each cylinder half being arranged in a plurality of rows with the ports of one row opposite the closed spaces of another row, so as to be successively closed by the advancing piston, the cylinder also having an unloading-port located between the regulating-ports belonging to the opposite longitudinal halves of the cylinder, regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order, and an automatic governor in control of the regulating means.

16. A double-acting pump comprising a cylinder, a reciprocatable piston therein, the cylinder in each longitudinal half thereof having a plurality of regulating-ports arranged at successively different points in the path of the piston so as to be successively closed by the advancing piston, the cylinder also having an unloading-port located between the regulating-ports belonging to the opposite longitudinal halves of the cylinder, regulating means in control of the regulating-

ports and actuatable to open the regulating-ports for each longitudinal half of the cylinder successively from the middle of the cylinder toward the ends thereof and to close the regulating-ports for each longitudinal half of the cylinder successively in the reverse order, and an automatic governor in control of the regulating means.

17. A pump comprising a cylinder, a piston therein, a supply-conduit and a closable inlet for the cylinder, the cylinder having an unloading-port in the path of the delivery end of the piston and communicating with the supply-conduit in advance of the closable inlet, whereby discharge may be made back into the supply-conduit during a portion of the piston stroke and until the unloading-port has been covered by the piston.

18. A pump comprising a cylinder, a piston therein, a supply-conduit and a closable inlet for the cylinder, the cylinder having a regulating-port in the path of the delivery end of the piston and communicating with the supply-conduit in advance of the closable inlet, and a regulating-valve in control of the regulating-port, whereby, when the regulating-port is open, discharge may be made back into the supply-conduit until the regulating-port has been covered by the piston.

19. A pump comprising a cylinder, a piston therein, a supply-conduit and a closable inlet for the cylinder, the cylinder having a plurality of regulating-ports at successively different points in the path of the delivery end of the piston and communicating with the supply conduit in advance of the closable inlet, and regulating means in control of the regulating-ports and actuatable to open the regulating-ports successively in the order of the direction of the delivery movement of the piston and to close the regulating-ports successively in the reverse order.

20. A pump comprising a cylinder, a piston therein, a supply-conduit and a closable inlet for the cylinder, the cylinder having a regulating-port in the path of the delivery end of the piston and communicating with the supply-conduit in advance of the closable inlet, whereby discharge may be made back into the supply conduit during a portion of the piston stroke and until the regulating port is covered by the piston, a regulating valve in control of the regulating-port, and an automatic governor in control of the regulating-valve.

21. A pump comprising a cylinder, a piston therein, a supply-conduit and a closable inlet for the cylinder, the cylinder having a plurality of regulating-ports at successively different points in the path of the delivery end of the piston and communicating with the supply conduit in advance of the closable inlet, regulating means in control of the regulating-ports and actuatable to open the regu-

lating-ports successively in the order of the direction of the delivery movement of the piston and to close the regulating-ports successively in the reverse order, and an automatic governor in control of the regulating means.

22. A pump comprising a cylinder, a piston therein, a supply-conduit and a closable inlet for the cylinder, the cylinder having a plurality of regulating-ports at successively different points in the path of the delivery end of the piston and communicating with the supply-conduit in advance of the closable inlet, and regulating means in control of the regulating-ports and actuatable to open the regulating-ports successively in the order of the direction of the delivery movement of the piston and to close the regulating-ports successively in the reverse order, the cylinder also having an unloading port arranged so as to be closed by the piston in advance of the regulating-ports and permanently communicating with the supply-conduit in advance of the closable inlet, and regulating means in control of the regulating-ports and actuatable to open the regulating-ports successively in the order of the direction of the delivery movement of the piston and to close the regulating-ports successively in the reverse order, the cylinder also having an unloading port arranged so as to be closed by the piston in advance of the regulating-ports and permanently communicating with the supply-conduit in advance of the closable inlet.

23. A pump comprising a cylinder, a piston therein, a supply-conduit and a closable inlet for the cylinder, the cylinder having a plurality of regulating-ports at successively different points in the path of the delivery end of the piston and communicating with the supply-conduit in advance of the closable inlet, the regulating-ports being arranged in a plurality of rows with ports of one row opposite the closed spaces of another row, and regulating means in control of the regulating-ports and actuatable to open the regulating-ports successively in the order of the direction of the delivery movement of the piston and to close the regulating-ports successively in the reverse order.

24. A pump comprising a cylinder, a piston therein, a supply-conduit and a closable inlet for the cylinder, the cylinder having a plurality of regulating-ports at successively different points in the path of the delivery end of the piston and communicating with the supply-conduit in advance of the closable inlet, the regulating-ports being arranged in a plurality of rows with ports of one row opposite the closed spaces of another row, regulating means in control of the regulating-ports and actuatable to open the regulating-ports successively in the order of the direction of the delivery movement of the piston and to close the regulating-ports successively in the reverse order, and an automatic governor in control of the regulating means.

25. A pump comprising a cylinder, a piston therein, a supply-conduit and a closable inlet for the cylinder, the cylinder having a plurality of regulating-ports at successively different points in the path of the delivery end of the piston and communicating with the supply-conduit in advance of the closable inlet, the regulating-ports being arranged in a plurality of rows with ports of one row opposite the closed spaces of another row, and regulating means in control of the regulating-ports and actuatable to open the regulating-ports successively in the order of the direction of the delivery movement of the piston and to close the regulating-ports successively in the reverse order, the cylinder also having an unloading port arranged so as to be closed by the piston in advance of the regulating-ports and permanently communicating with the supply-conduit in advance of the closable inlet, and regulating means in control of the regulating-ports and actuatable to open the regulating-ports successively in the order of the direction of the delivery movement of the piston and to close the regulating-ports successively in the reverse order, the cylinder also having an unloading port arranged so as to be closed by the piston in advance of the regulating-ports and permanently communicating with the supply-conduit in advance of the closable inlet, and regulating means in control of the regulating-ports and actuatable to open the regulating-ports successively in the order of the direction of the delivery movement of the piston and to close the regulating-ports successively in the reverse order.

able inlet, the regulating-ports being arranged in a plurality of rows with ports of one row opposite the closed spaces of another row, the cylinder also having an unloading-port arranged so as to be closed by the piston in advance of the regulating-ports and permanently communicating with the supply-conduit in advance of the closable inlet, and regulating means in control of the regulating-ports and actuatable to open the regulating-ports successively in the order of the direction of the delivery movement of the piston and to close the regulating-ports successively in the reverse order.

26. A double-acting pump comprising a cylinder, a reciprocatable piston therein, a supply-conduit and inlet valves for the cylinder, the cylinder in each longitudinal half thereof having a plurality of regulating-ports at successively different points in the path of the piston and communicating with the supply-conduit in advance of the inlet-valves, and regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order.

27. A double-acting pump comprising a cylinder, a reciprocatable piston therein, a supply-conduit and inlet-valves for the cylinder, and a discharge-conduit for the cylinder, the cylinder having an unloading-port located in the path of the piston so as to be closed and passed by the piston in both directions of piston travel and permanently communicating with the supply-conduit in advance of the inlet-valves, whereby in each direction of piston movement discharge takes place back into the supply-conduit until the unloading-port is closed by the advancing piston.

28. A double-acting pump comprising a cylinder, a reciprocatable piston therein, a supply-conduit and inlet-valves for the cylinder, and a discharge-conduit for the cylinder, the cylinder having an unloading-port located medially of the limits of piston travel, so as to be closed and passed by the piston in both directions of piston movement, and permanently communicating with the supply-conduit in advance of the inlet-valves.

29. A double-acting pump comprising a cylinder, a reciprocatable piston therein, a supply-conduit and inlet-valves for the cylinder, the cylinder in each longitudinal half thereof having a plurality of regulating-ports at successively different points in the path of the piston and communicating with the supply-conduit in advance of the inlet-valves, the regulating-ports for each cylinder half being arranged in a plurality of rows with ports of one row opposite the closed spaces of another row, and regulating means in control of the regulating-ports and actuatable to open the regulating-ports successively in the order of the direction of the delivery movement of the piston and to close the regulating-ports successively in the reverse order.

with the ports of one row opposite the closed spaces of another row, and regulating means in control of the regulating-ports and actuatable to open the regulating-ports for each 5 longitudinal half of the cylinder successively from the middle of the cylinder toward the ends thereof and to close the regulating-ports for each longitudinal half of the cylinder successively in the reverse order.

30. A double-acting pump comprising a cylinder, a reciprocatable piston therein, a supply-conduit and inlet-valves for the cylinder, the cylinder in each longitudinal half thereof having a plurality of regulating-ports at successively different points in the path of the piston and communicating with the supply-conduit in advance of the inlet-valves, the cylinder also having an unloading-port therein located between the regulating-ports belonging to the opposite longitudinal halves of the cylinder and permanently communicating with the supply-conduit in advance of the inlet-valves, and regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order.

31. A double-acting pump comprising a cylinder, a reciprocatable piston therein, a supply-conduit and inlet-valves for the cylinder, the cylinder in each longitudinal half thereof having a plurality of regulating-ports at successively different points in the path of the piston and communicating with the supply-conduit in advance of the inlet-valves, the regulating-ports for each cylinder half being arranged in a plurality of rows with the ports of one row opposite the closed spaces of another row, the cylinder also having an unloading-port therein located between the regulating-ports belonging to the opposite longitudinal halves of the cylinder and permanently communicating with the supply-conduit in advance of the inlet-valves, and regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order.

32. A double-acting pump comprising a cylinder, a reciprocatable piston therein, a supply-conduit and inlet-valves for the cylinder, the cylinder in each longitudinal half thereof having a plurality of regulating-ports at successively different points in the path of the piston and communicating with the supply-conduit in advance of the inlet-valves, regulating means in control of the regulating-

ports and actuatable to open the regulating-ports for each longitudinal half of the cylinder successively from the middle of the cylinder toward the ends thereof and to close the regulating-ports for each longitudinal half of the cylinder successively in the reverse order, and an automatic governor in control of the regulating means.

33. A double-acting pump comprising a cylinder, a reciprocatable piston therein, a supply-conduit and inlet-valves for the cylinder, the cylinder in each longitudinal half thereof having a plurality of regulating-ports at successively different points in the path of the piston and communicating with the supply-conduit in advance of the inlet-valves, the regulating ports for each cylinder half being arranged in a plurality of rows with the ports of one row opposite the closed spaces of another row, regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order, and an automatic governor in control of the regulating means.

34. A double-acting pump comprising a cylinder, a reciprocatable piston therein, a supply-conduit and inlet-valves for the cylinder, the cylinder in each longitudinal half thereof having a plurality of regulating-ports at successively different points in the path of the piston and communicating with the supply-conduit in advance of the inlet-valves, the cylinder also having an unloading-port therein located between the regulating-ports belonging to the opposite longitudinal halves of the cylinder and permanently communicating with the supply-conduit in advance of the inlet-valves, regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the reverse order, and an automatic governor in control of the regulating means.

35. A double-acting pump comprising a cylinder, a reciprocatable piston therein, a supply-conduit and inlet-valves for the cylinder, the cylinder in each longitudinal half thereof having a plurality of regulating-ports at successively different points in the path of the piston and communicating with the supply-conduit in advance of the inlet-valves, the regulating-ports for each cylinder half being arranged in a plurality of rows with the ports of one row opposite the closed spaces of another row, the cylinder also having an unloading-port therein located between the regulating-ports belonging to the opposite longitudinal halves of the cylinder

and permanently communicating with the supply-conduit in advance of the inlet valves, regulating means in control of the regulating-ports and actuatable to open the regulating-ports for each longitudinal half of the cylinder successively from the middle of the cylinder toward the ends thereof and to close the regulating-ports for each longitudinal half of the cylinder successively in the re-

verse order, and an automatic governor in control of the regulating means.

In testimony whereof I have affixed my signature in presence of two witnesses.

LOUIS K. DOELLING.
